MINE CAR LOADER

Dallas W. Poston, Kimberly, Nev.
Application September 13, 1943, Serial No. 502,172

2 Claims. (Cl. 214—110)

This invention relates to a mine car loader, and has for the primary object the provision of a portable device of this character which will conveniently operate in a mine drift or lateral to rapidly load ore into a mine car brought into the drift or lateral and may be easily moved in the drift or lateral relative to the ore as mined. With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating a loader constructed in accordance with my invention and showing said loader arranged in a mine drift or lateral for the purpose of loading a mine car with ore.

Figure 2 is a top plan view illustrating the same.

Figure 3 is a transverse sectional view taken on the line 3—3 of Figure 1.

Figure 4 is a fragmentary transverse sectional view showing one of the adjusting means for the ramp forming a part of the present invention.

Figure 5 is a plan view, partly in section, illustrating a boom.

Referring in detail to the drawings, the numeral 5 indicates a car capable of traveling on a mine track and is employed in the construction of the present invention to render the latter portable. The car 5 is equipped with a turntable 6 carrying a body 7 on which is adjustably mounted a ramp 8 including an inclined portion 9 and a substantially horizontal portion 10 provided with a discharge opening 11 (see Figure 2). The inclined portion 9 is of sectional formation, the sections being connected by a hinge 12 (see Figure 1) which will permit one section to be folded on the other section when the device is not in use.

This arrangement facilitates the movement of the device within a mine drift or lateral, indicated by the character A.

One of the sections of the inclined portion 9 is adapted to rest with its outer end upon the floor of the drift or lateral when the device is in use so that a scraper 13 may easily move onto and off of the ramp. The receiving end of the ramp is somewhat flared transversely to permit

the scraper to freely move on and off of the ramp.

The scraper 13 includes a scraper blade 14 with converging arms 15 integral therewith and connected with each other and to which a pull cable 16 is connected. The scraper blade 14 is provided with an eye 17 on its rear face to which a pull-back cable 18 is connected (see Figure 1). A platform 19 is mounted on the body 7 and includes vertically arranged and spaced side supporting members 20 between which extends the ramp 8. Some of the supporting members 20 are provided with a series of openings 21 for the accommodation of an adjusting rod 22 which supports the ramp and permits the latter to be raised and lowered by the rearrangement of the adjusting rod in the openings. The ramp has a depending member 22 secured thereto and provided with a series of openings received within a bracket 23 on the body 7. A pin 24 is removably carried by the bracket and may enter any one of the openings of the depending member 22 to permit adjustment of the ramp on the body 7 (see Figure 3).

25 The turntable 6 permits the body 7 and ramp 8 to be swung laterally for the purpose of bringing the receiving end of the ramp in proper location with respect to the ore, designated by the character B, and for bringing the opening 11 over a mine car 26.

26 The platform 19 supports a power driven winch 27 controlled by a clutch mechanism 28. The cable 16 is secured to and wound on one of the drums of the winch, while the other drum there-
35 of has the cable 18 secured thereto and partly wound thereon. The cable 16 travels over the floor of the ramp and over a pulley 29 before reaching its respective drum.

30 The cable 18 after leaving its drum passes over a tail pulley 30 carried by a boom 31.

31 The boom 31 consists of detachably connected sections whereby its length may be varied. The boom is pivotally mounted on the platform 19, as shown at 32, and is supported rearwardly of the body 7 by a brace 33. To vary the elevation of the pulley 30 at the free end of the boom shorter or longer braces 33 may be employed. The free end of the boom carrying the pulley 30 is arranged over and in close proximity to the ore to be loaded, so that the scraper can be drawn to a position to engage with the ore and take a portion thereof onto the ramp and carry the engaged ore up the ramp and discharge the same into the mine car by way of the opening 11.

35 It is to be understood that the forward and

rearward movement of the scraper is controlled by the operation of the winch 27 in opposite directions.

When a lateral or drift is first started in a mine, there may not be sufficient room for the accommodation of the boom and if this occurs, the pulley 30 may be demounted from the boom and the latter from the turntable and the pulley anchored into the wall of the drift or lateral so that the pull-back cable 18 will be properly positioned to bring the scraper into gathering position on the pile of ore. However, when the lateral or drift has been advanced sufficient to permit the use of the boom, the latter is restored into operation on the platform with the pulley 30 in place thereon.

Through the use of the boom for supporting the pull-back cable, as shown in Figure 1, the car 5 and body 7 is permitted to be located at a considerable distance from the ore which has been mined. This distance is sufficient to permit additional rails of the track to be laid as the work advances in the mine. Also the arrangement of the boom permits miners to mine ore while the device is in the action of loading ore onto a car.

A loader of the kind described in the foregoing specification and shown in the drawings will be extremely simple to operate, economical to manufacture and will efficiently and rapidly load ore onto a mine car.

While I have shown and described the preferred embodiment of my invention, it will be understood that minor changes in construction, combination and arrangement of parts may be

made without departing from the spirit and scope of the invention as claimed.

Having thus described my invention, what I claim is:

5. In a mine car loader, a portable conveyance including a turntable supporting a body, a ramp extending longitudinally of the body and projecting forwardly and rearwardly therefrom, means for adjusting the front and rear ends of the ramp on the body, a scraper for gathering materials longitudinally and moving said materials over the ramp from front to rear thereof, and a compensating power means carried by the body and connected to the scraper for moving the latter in opposite directions in working relation to the ramp in all adjusted working positions of the ramp.
10. In a mine car loader, a portable conveyance including a turntable supporting a body, a ramp extending longitudinally of the body and including an inclined portion and a horizontal portion having a discharge opening, said inclined portion consisting of a hingedly connected outer section projecting rearwardly of the body with one end engageable with the ground, means for vertically adjusting the inclined portion on the body, a scraper for movement over the ramp and for gathering material, a power driven operating means including flexible cables connected to the scraper, said power operating means carried by the body, and a boom for guiding the movement of one of the cables.
15. In a mine car loader, a portable conveyance including a turntable supporting a body, a ramp extending longitudinally of the body and including an inclined portion and a horizontal portion having a discharge opening, said inclined portion consisting of a hingedly connected outer section projecting rearwardly of the body with one end engageable with the ground, means for vertically adjusting the inclined portion on the body, a scraper for movement over the ramp and for gathering material, a power driven operating means including flexible cables connected to the scraper, said power operating means carried by the body, and a boom for guiding the movement of one of the cables.
20. In a mine car loader, a portable conveyance including a turntable supporting a body, a ramp extending longitudinally of the body and including an inclined portion and a horizontal portion having a discharge opening, said inclined portion consisting of a hingedly connected outer section projecting rearwardly of the body with one end engageable with the ground, means for vertically adjusting the inclined portion on the body, a scraper for movement over the ramp and for gathering material, a power driven operating means including flexible cables connected to the scraper, said power operating means carried by the body, and a boom for guiding the movement of one of the cables.
25. In a mine car loader, a portable conveyance including a turntable supporting a body, a ramp extending longitudinally of the body and including an inclined portion and a horizontal portion having a discharge opening, said inclined portion consisting of a hingedly connected outer section projecting rearwardly of the body with one end engageable with the ground, means for vertically adjusting the inclined portion on the body, a scraper for movement over the ramp and for gathering material, a power driven operating means including flexible cables connected to the scraper, said power operating means carried by the body, and a boom for guiding the movement of one of the cables.
30. In a mine car loader, a portable conveyance including a turntable supporting a body, a ramp extending longitudinally of the body and including an inclined portion and a horizontal portion having a discharge opening, said inclined portion consisting of a hingedly connected outer section projecting rearwardly of the body with one end engageable with the ground, means for vertically adjusting the inclined portion on the body, a scraper for movement over the ramp and for gathering material, a power driven operating means including flexible cables connected to the scraper, said power operating means carried by the body, and a boom for guiding the movement of one of the cables.

DALLAS W. POSTON.
